PHOTOMETER

Frank F. Crandell, Pasadena, and George D. Perkins,
Van Nuys, Calif., assignors to Photo Research Corporation,
Burbank, Calif., a corporation of California

Application February 8, 1954, Serial No. 28,910

Term of patent 14 years

(Cl. D61—1)

FIG. 1.

FIG. 2.

FIG. 3.

FIG. 4.

To all whom it may concern:

Be it known that we, Frank F. Crandell and George D. Perkins, citizens of the United States and residents of Pasadena and Van Nuys respectively, in the county of Los Angeles and State of California, have invented a new, original, and ornamental Design for Photometer, of which the following is a specification, reference being had to the accompanying drawing, forming a part hereof.

Fig. 1 is a top plan view of a photometer showing our new design.

Fig. 2 is a side elevational view thereof.

Fig. 3 is a bottom view thereof.

Fig. 4 is a front elevational view thereof.

The dominant feature of our design resides in the portions shown in full lines.

We claim:

The ornamental design for a photometer, substantially as shown and described.
